ELECTRONIC TUBE

Max Orlove, New York, N. Y., assignor of one-half to Charles Schiffman, New York, N. Y.

Application November 7, 1942, Serial No. 464,840

13 Claims. (Cl. 176—122)

1

This invention relates to electronic tubes. More particularly, the invention pertains to electronic tubes of the type in which the conventional fragile incandescent filament is supplanted by an electron-emissive substance energized by means other than an extremely high temperature.

One of the objects of the invention is to provide an improved tube of the character described which is light in weight and rugged in design, consumes relatively little power for releasing electrons, is highly sensitive, and is adapted to be efficiently employed in the usual circuits in which present-day electronic tubes can be used.

Another object of the invention is to provide a tube of the character described in which electrons are released from the electron-emissive substance under the influence of only a moderate or mild temperature of the order of that generated in or by a glow discharge.

Another object of the invention is to provide a tube of the character described in which a plurality of separate groups of tube elements are contained in a single envelope and in which but a single means is employed to economically, simply and efficiently energize independent electron-emissive elements associated with the several groups of tube elements.

A further object of the invention is to provide a tube of the character described which is particularly adaptable for use in roughly handled portable sets and in which the energy required to release electrons can be supplied by a source of light weight and small capacity.

Another object of the invention is to provide a tube of the character described in which the electron-emissive substance is not electrically connected in the circuit in which the tube is employed, whereby the tube is rendered extremely sensitive, the tube's space charge and electron emission from coated surfaces is unaffected by current flowing through the heated filament, and the uneven emission of electrons due to variation of potential applied to the heated filament is eliminated.

A still further object of the invention is to provide a tube of the character described in which the use of costly and critical metals, such as tungsten and nickel, is avoided.

Another object of my invention is to provide a tube of the character described which can operate even when the electrodes are enclosed in an unevacuated container.

Still another object of the invention is to provide a tube of the character described which is rendered highly sensitive by novel shielding.

2

Other objects of the invention will in part be obvious and in part hereinafter pointed out.

The invention accordingly consists in the features of construction, combinations of elements, and arrangement of parts which will be exemplified in the constructions hereinafter described, and of which the scope of application will be indicated in the appended claims.

Certain features of the invention shown and described but not claimed herein are described and claimed in my copending application, Serial No. 464,841, for Electron tube coating, filed on the 7th day of November 1942, which issued September 30, 1947, as United States Patent Number 2,428,289.

In the accompanying drawings, in which is shown one of the various possible embodiments of this invention,

Fig. 1 is a side view in partial section of an electronic tube embodying my invention;

Fig. 2 is a sectional view taken substantially along the line 2—2 of one of the finger tubes shown in Fig. 1;

Figs. 3 and 4 are enlarged sectional views taken substantially along the lines 3—3 and 4—4 respectively of Fig. 1;

Fig. 5 is an end view of one of the finger tubes;

Fig. 6 is an end view of a coupling socket adapted to be used therewith;

Fig. 7 is a view, similar to Fig. 1, of an electric tube embodying a modified form of my invention;

Fig. 8 is an enlarged sectional view taken substantially along the line 8—8 of Fig. 7;

Fig. 9 is a side view of an electronic tube embodying another modified form of my invention; and

Fig. 10 is a sectional view taken substantially along the line 10—10 of Fig. 9.

Referring now to the drawings, and more particularly to Figs. 1 through 6, wherein there is disclosed one of the preferred forms of my invention, 20 denotes a compound electronic tube embodying my invention. Said tube comprises a trunk tube 22 preferably fabricated from a dielectric substance, such as glass or a plastic. The trunk tube is elongated and has disposed at its two reduced ends cup-shaped electrodes 24, 26 which are supported and adapted to be connected in circuit by lead-in wires L. The interior of the trunk tube 22 is filled with an inert ionizable gaseous medium at a low pressure so that when a proper potential is applied to the electrodes 24, 26 a glow discharge will be maintained therebetween. The potential supplied to the electrodes and the type and pressure of gas contained with-

in the trunk tube may be such that a positive column electric discharge will occur between said electrodes. Any suitable means (not shown) may be employed to initiate a discharge between said electrodes.

The heat of such discharge and that generated by bombardment of objects in the path of the electron stream is employed, in a manner soon to be described, as the means for energizing one or more electron-emissive elements. These elements are associated with the electrodes of one or more separate groups of tube elements, each of which groups is adapted to be used in place of a present day electronic tube. This heat may be enhanced, if desired to raise the electron-emission rate, by incorporating an easily vaporizable metal such as mercury in the trunk tube.

Although I have in this embodiment of my invention, and other embodiments which will later be described, illustrated the trunk tube as having a straight elongated envelope, I wish to make it clear that other forms of envelopes may be employed. For example, I contemplate the use of spherical and semi-spherical envelopes and of annular envelopes. These forms may be found desirable under certain circumstances where, for example, only a limited space is provided for housing the parts of an electron tube circuit.

It will be understood that any suitable means (not shown) may be employed to firmly and detachably support the tube 20 in position within the circuit housing.

Also in accordance with my invention I provide in association with the trunk tube 22 a plurality of finger tubes 28, 30 and 32 each of which contains a substance, preferably in the form of a coating, which under the energization of the glow discharge in the tube 22 will emit a copious flow of electrons.

Essentially each finger tube, in addition to the coating, comprises an envelope and a set of electrodes whose design is governed by the use to which the tube is put. Optionally and preferably the tube may further include means projecting into the path of the electron stream in the trunk tube 22 whereby the finger tube is heated with a minimum expenditure of energy in the trunk tube. Other optional structure may include high heat conductivity means intermediate the finger tubes and trunk tube, means to detachably attach finger tubes to the trunk tube, use of unevacuated finger tubes, partially saturated magnetic shielding, couplings for connecting the finger tubes to conventional vacuum tube sockets, inclusion of a plurality of separate groups of tube elements within a single finger tube and the provision therewith of means for isolating the separate groups of elements, connection of the interior of finger tubes to the interior of the trunk tube, and screening finger tube electrodes from the magnetic field and electron stream of the trunk tube.

The finger tubes 28, 30 and 32 are supported by the trunk tube 22 and may vary in number from one up to as many electronic tubes as are needed in circuit. Of course, if desired, a lesser number of tubes than need be used in a circuit may be associated with the trunk tube 20.

The finger tube 28, which is of the rectifier type, comprises a cylindrical glass envelope 34 fused to the envelope of the trunk tube 22 and opening into the interior thereof. The projecting end of the finger tube envelope 34 is provided with a retroverted press 36 and base 38 in a manner well known in the electronic tube art.

The press 36 supports, by means of lead wires 40, a cathode 42 comprising a flat plate of electrically conductive metal an anode 44 of the same material and structure as the cathode 42. The cathode and anode are disposed in parallel, closely spaced relationship.

One of the lead wires 40 carries a latticed screening electrode 46 which substantially covers the opening interconnecting the envelope 34 and trunk tube 22.

Three pins 48 project from the base of the socket 38, each pin being connected with a different lead-in wire 40 in a conventional manner. If desired, one of the pins 48, for example the pin which is electrically connected to the screening electrode 46, may be made slightly larger than the pins connected to the anode and cathode whereby a coupling plug 50 having socket connectors 52 can be automatically correctly oriented with respect to the base 38. Said plug 50 is connected by lead wires 54 to another plug 56 having prongs 58 projecting therefrom and adapted to be received in a standard electronic tube socket.

It will be understood, of course, that in sets or instruments especially designed and built for use with my electronic tube, the sockets may be disposed in such relationship as to directly receive the prongs 48 extending from the bases of the several finger tubes 28, 30, 32. In such case, I may arrange all of said finger tubes with their bases in the same or parallel planes to facilitate simultaneous insertion of all the prongs 48 in their sockets.

The interior of the finger tube is coated with a substance which, under the influence of the heat generated in and by the glow discharge in the trunk tube 22, will emit a copious flow of electrons sufficient to carry the desired current between the electrodes 42, 44.

Said coating is preferably of the type described in my said copending application and may comprise a layer 59 of copper deposited on the interior surface of the envelope 34, a spray-coated base layer 60 (Figs. 1 and 2) of a mixture of selenium and copper oxide on the copper layer, and a layer 62 of an electron-emissive substance such as barium, strontium, cesium, thorium or virginium oxide deposited on the base layer. A typical base layer is fifty per cent by weight of selenium and fifty per cent by weight of copper oxides intimately mixed and finely sub-divided, and held to the glass envelope 34 by any suitable binder. A typical electron-emissive layer is 33 1/3%, by weight of barium oxide, 16 2/3%, by weight of strontium oxide, and 50%, by weight of cesium oxide. The compounds in this layer are also finely subdivided and intimately mixed. The base layer is extremely thin and the electron-emissive layer, which deteriorates during use, is thicker.

I have found that a coating of the above composition will emit an extremely copious flow of electrons at moderate temperatures of the order of those generated by a glow discharge, such as that in a positive column discharge tube. A secondary electron emission arising from bombardment of the coating by the emitted electrons increases the electron emission of the coating.

The electrons emitted from the coating are employed to carry a unidirectional current from the cathode 42 to the anode 44. A negative charge is imposed upon the screening electrode 46 to prevent stray electron flow through the

opening between the finger tube envelope 34 and trunk tube 22.

The finger tube 30 comprises a tubular glass envelope 64 having an integral, domed, imperforate bottom wall 66 which is fused to the wall of the trunk tube 22 and which projects well into the interior of said trunk tube so that it will lie in the path of and be bombarded by the electron stream between the trunk electrodes 24, 26. The opposite end of the glass tube 64 is retroverted to provide a press 68 which supports lead-in wires 70 for a cathode 72, grid 74, and plate 76. These three electrodes 72-76 comprise open-ended tubular elements concentrically arranged and preferably disposed coaxially of the tubular envelope 64. The cathode 72, which is outermost of the three electrodes, comprises a plurality of parallel spaced wires 78 arranged to form a cylinder and supported on spaced rings 79. The grid 74 is a metal screen and the anode an imperforate metal sheet.

The lead-in wires 70 are connected in the usual manner to prongs (not shown) in the base 80 of the finger tube 30. Said prongs are connected by a coupling, like that shown for the finger tube 28, to a socket in the circuit in which the tube 30 is to be employed.

The interior surface of the finger tube 30 is provided with an electron emissive coating like that described with reference to the finger tube 28.

In the operation of the tube electrons emitted from the coating enter the space between the anode 76 and cathode 72 and conduct current therebetween, such current being controlled by the grid 74 in the well-known manner.

It will be appreciated that, due to the thermal capacity of the envelope 64, the coating is maintained at a uniform temperature and electron-emission therefrom occurs at a uniform rate. This does away with the use of filter circuits heretofore employed to eliminate an A. C. hum caused by intermittent heating of a filament. Dispensing with a heater filament also eliminates interference arising from undesirable electron-emission of the filament and passage of current therethrough.

The finger tube 32 comprises a glass tubular envelope 82 closed at one end by an imperforate domed bottom 84. Said tube is adapted to be snugly received in an annular flange 86 extending from the wall of the trunk tube 22. To provide better heat conductivity for the finger tube 32 and to thus increase the temperature to which its coating (similar to that of the other finger tubes) is raised, and increase electron-emission, I also employ a hemispherical metallic shell 90 projecting into the interior of the trunk tube and having a short integral tubular extension 92 which is fused to the interior of the annular flange 86 and seals the opening in said trunk tube. The shell 90 is of such configuration as to snugly receive the bottom of the finger tube 32.

Said finger tube is closed at its free end and is there provided with a retroverted press 94 in which the lead-in wires 96 are carried. The interior of the tube envelope, including the domed bottom 84, is provided with three metallic-coated segments 98 which may be of equal size and, together, cover substantially the entire inner surface of the finger tube with the exception of a narrow space between the coatings. Each metallic segment is connected by a lead-in wire 96 to a prong (not shown) in the base 100 of the finger tube 32. Each metallic segment 98 has super-

imposed thereon a base layer 102 and an overlying electron-emissive layer 104 such as were described with reference to the finger tube 28.

Intermediate adjacent edges of the metallic segments are electrically conductive barrier plates 106 which extend radially toward the center of the finger tube and are connected by lead-in wires 96 to prongs in the base of the tube. Said barrier plates physically separate the tube into a plurality of sectors. These barriers are adapted to be negatively charged during operation of the tube to electrically segregate said sectors and prevent groups of electrodes disposed in different sectors from interfering with each others operation.

Associated with each segmental electron-emissive coating is a segmental screen wire grid 108 which lies between the coating and the center of the tube and extends angularly between but does not touch the two barrier plates 106 which bound each sector. Each coating and grid also has associated therewith a segmental electrically conductive metallic anode 110 which lies closer to the center of the tube than the grid and, like the grid, does not touch the barrier plates. The segmental coating, grid, and anode comprise an electrode group. The three electrode groups in the finger tube 32 are concentrically arranged about the longitudinal axis of said tube. Obviously if other electrodes are employed in any electrode group they may be placed in proper order within the boundaries defined by the barrier plates 106 and metallic coating 98.

The same type of coupling means as was described with reference to the finger tube 28 may be employed to detachably attach the prongs in the base 100 to various conventional sockets for electronic tubes.

It will be noted that in a finger tube of this construction a plurality of electrode groups are enclosed within a single tube so that said tube can replace several present-day electronic tubes. The number of electrode groups that can be contained within a single tube is only limited by the size of the tube and the nature of the circuit in which the electrode groups are to be employed.

It will also be noted that in the finger tube just described the electron-emissive coating is employed as a cathode and that it is adapted to have potential from a circuit applied thereto.

I have found that the operation of the several finger tubes 28, 30, 32 and of the trunk tube 22 is appreciably enhanced by shielding said trunk and finger tubes with an unsaturated but partially magnetized magnetic material.

The shield may take the form illustrated in Figs. 1 through 4, that is, it may comprise a main tubular portion 112 telescopically disposed around the trunk tube 22. Said tubular portion has a plurality of tubular projections 114, 116, 118 adapted to be telescopically received around the finger tubes 28, 30, 32 respectively. The shielding may be constructed and assembled in any desired manner. For instance, the main tubular portion 112 may comprise two adhesively joined segments to which the projecting tubular portions 114, 116 and 118 may be adhesively secured.

In accordance with my invention the substance from which the shielding is fabricated comprises a magnetic plastic. This includes a matrix of any plastic substance which is not deleteriously affected by the operating temperatures of the tube. By way of example, and without limiting myself to such materials, this substance may

comprise either of the compositions known commercially as "Bakelite" and "Texolite." Uniformly distributed throughout the plastic matrix are finely subdivided particles of a ferrous material such as soft iron, having a high magnetic permeability but incapable of retaining anything but a slight residual magnetism. The plastic matrix also has uniformly distributed there-through finely subdivided particles of a highly magnetically permeable material, such as steel, which is capable of retaining magnetism. This later substance before incorporation into the matrix is magnetized. Thus the magnetic plastic substance which shields the tube 20 at all times creates a magnetic field but is not saturated.

The presence of this field, I believe, caused by the tubular projections 114, 116, 118 tends to force the electrons emitted from the electron-emissive coatings of the finger tubes toward the center of such tubes so that they will be available in large quantities to conduct current between the cathode and anode. In addition, during operation of the tube the electric fields induced by the operating current increases the magnetization of the shield by temporarily magnetizing the soft iron particles, thus enhancing the effect of the magnetic plastic shielding. I have also found that the magnetic plastic shield 112 around the trunk tube 22 reduces the power consumption thereof in generation of the glow, thus increasing the power efficiency of the tube 20. This is probably due to the same cause as that explained with reference to the shields for the finger tubes. The term "power efficiency" as used herein denotes the ratio between the quantity of electrons emitted by the electron-emissive coatings and the amount of power required to emit such electrons.

It will be further appreciated that by energizing a plurality of finger tubes from a single trunk tube the power efficiency of the tube 20, even when magnetic plastic shielding is not employed, is considerably greater than has heretofore been obtained.

Due to the exceedingly copious flow of electrons secured by the use of the coating previously described, it is even possible to operate the finger tubes 28, 30 and 32 in unevacuated envelopes. This adaptation of the finger tubes is rendered more efficient, of course, by the presence of the magnetic plastic shielding.

I found that the efficiency of the magnetic shield is increased by providing air gaps G each having a component running axially of the tubular portions of the shielding with which it is associated.

If desired, one or more of the finger tubes may be supplementally or even independently heated to the desired moderate emitting temperature by a resistance winding 120 about such tube. This winding is illustrated in Fig. 1 in conjunction with the finger tube 30 as a supplemental source of heat so that said tube can have a higher power output than the finger tube 32.

By supplying potential to the resistance winding 120 from a portion of the circuit in which the tube 30 is connected I may further periodically strengthen the magnetic field forcing coated electrons to the center of the tube in phase with the periodic potential applied to the grid, thus increasing the sensitivity of the tube. For this purpose the resistance winding 120 is in the form of a helix wrapped around the tubular

5 magnetic plastic shielding 116 to act as an inductance.

Although I have illustrated the several finger tubes supported on the trunk tube 22 as being of the same size and two of the finger tubes as having different types of electrodes, it will be understood that these tubes may be of various sizes and all employ similar electrodes.

It will also be understood that, regardless of number, all or less than all of the finger tubes required in an electric circuit may be carried by the same trunk tube.

In Figs. 7 and 8, I have illustrated an electron tube 130 embodying another form of my invention. In this form the glass trunk tube 132, which functions in the same manner as the trunk tube 22, is enclosed for substantially its full length in a tubular glass envelope 134. In the annular space provided between the envelope 134 and the external surface of the trunk tube, 20 I dispose a plurality of electrode groups 136, 138, 140, each of which is adapted to serve as an independent electronic tube.

The group 136 is adapted to act as a rectifier and includes a cathode 142 and anode 144. The cathode 142 is a foraminous tubular element of a conductive material which is telescopically disposed around and is coaxial with the tube 132. The anode is an imperforate tubular member of conductive material telescopically disposed around the cathode 142 and also arranged coaxially of the trunk tube 132. Both cathode and anode are connected by lead-wires 146 to prongs 148 projecting from the base 150 of the electrode group 136. Said base is secured in any suitable manner as by cementing to the outer envelope 134. The portion of the surface of the trunk tube 132 within the cathode 142 carries a three-layered electron-emissive coating 152, such as described with reference to Figs. 1-6. The axial dimensions of this coating 152, the cathode 142, and anode 144 depend upon several factors, such, for example, as the power rating of the electrode group 136. If desired, the coating 152 may serve 30 as the cathode, although it will be understood that the characteristics of the electrode group in such case, are not the same as that of the electrode rectifier group previously described.

In general, electrode groups 138 and 140 may 50 be constructed in the same manner as the electrode group 136. I have illustrated both of these groups as comprising the equivalents of conventional three-element vacuum tubes. One of said groups, for example, the group 140, includes a cathode 154, a grid 156, and an anode 158. All 55 of these electrodes are disposed concentrically of the trunk tube 132 and supported on lead-in wires 160 which are electrically connected to prongs 162 in the base 164 for said electrode group. Both the cathode and grid are foraminous. The anode, however, may be imperforate. The coating 166 associated with this electrode group 140 is of the same composition as that 60 employed with the electrode group 136.

The outer envelope 134 is shielded by a cylinder 168 of a magnetic plastic material such as that described in the first embodiment of my invention.

The annular space between the envelope 134 and the envelope for the trunk tube is evacuated and free from oxygen.

The prongs in the bases for the various electrode groups 136, 138, 140 can be connected to conventional tube sockets by the detachable 70 couplings such as the couplings 54-58 illustrated

in Fig. 1, and the tube 130 itself can be removably supported in any suitable manner.

In Figs. 9 and 10, I have shown another modified form of my invention in which the electronic tube 170 is so constructed as to be disposed in a conventional electronic tube socket. Said tube 170 includes an outer envelope 172 of magnetic plastic (shown in dotted lines) such as that used to form the shields in the forms of my invention earlier described. The envelope 172 is of conventional shape and includes a retroverted press 174, a conventional base 176, and projecting connecting prongs 178. A small glow discharge tube 180 is supported on the press 174 by lead-in wires 182, 184. The envelope of said glow tube 180 has on its external surface a coating such as described at length with respect to the first embodiment of this invention. The cathode 185, grid 186, and anode 188 are all arranged concentrically of the discharge tube 180 and supported in this position by lead-in wires 190. Both the cathode and grids are foraminous and the anode imperforate.

It will be appreciated from the foregoing description that the electrode groups may be so designed as to accomplish any function of a present conventional electronic tube and they can thus be used as amplifiers, detectors, oscillators, cathode ray tubes, etc.

It will thus be seen that there are provided devices which achieve the several objects of this invention and which are well adapted to meet the conditions of practical use.

As various possible embodiments might be made of the above invention and as various changes might be made in the embodiments set forth, it is to be understood that all matter herein set forth or shown in the accompanying drawings is to be interpreted as illustrative and not in a limiting sense.

Having thus described my invention, I claim as new and desire to secure by Letters Patent:

1. An electronic tube comprising a member having a coating on said member adapted to emit a copious flow of electrons at a mild temperature in the order of that generated by a positive column, electric discharge lamp, and means comprising a positive column, electric discharge lamp to heat said coating to such mild temperature, said coating comprising a base layer adjacent said member and consisting essentially of two finely sub-divided and intimately physically mixed and uniformly distributed substances having different thermo-electric potentials, an electron-emissive layer on said base layer, said electron-emissive layer comprising an electron-emissive substance, and a layer of electrically conductive material intermediate said base layer and said member, the electrically conductive layer including a metal from the group consisting of copper and silver, the base layer comprising copper oxide and selenium, and the electron-emissive layer including an oxide selected from the group consisting of barium oxide, strontium oxide, cesium oxide, virginium oxide and thorium oxide.

2. An electronic tube comprising a member having a coating thereon which is energizable upon heating to primarily emit a copious flow of electrons and which coating carries no electric charge during operation of the tube, heating means to energize said coating for primary electron-emission, a cathode electrically insulated from said coating, an anode also insulated from said coating, and means to provide a magnetic field around said cathode and anode for direct-

ing between said cathode and anode the electrons emitted from said coating.

3. An electronic tube comprising a member having an electron-emissive coating thereon which carries no electric charge during operation of the tube, means to energize said coating to electron emission, a cathode electrically insulated from said coating, an anode, and means to provide a magnetic field around said cathode and anode for directing the electrons emitted from said coating between said cathode and anode, said last named means comprising a shield surrounding said tube, said shield being composed of a plastic matrix throughout which there is dispersed finely sub-divided magnetic material.

4. An electronic tube comprising a member having an electron-emissive coating thereon which carries no electric charge during operation of the tube, means to energize said coating to electron-emission, a cathode electrically insulated from said coating, an anode, and means to provide a magnetic field around said cathode and anode for directing the electrons emitted from said coating between said cathode and anode, said last named means comprising a shield surrounding said tube, said shield being composed of a plastic matrix throughout which there are dispersed finely sub-divided particles of temporarily highly magnetizable material and finely sub-divided permanently magnetized particles.

5. An electronic tube comprising a member having an electron-emissive coating thereon which carries no electric charge during operation of the tube, means to energize said coating to electron-emission, a cathode electrically insulated from said coating, an anode, and means to provide a magnetic field around said cathode and anode for directing the electrons emitted from said coating between said cathode and anode, said last named means comprising a magnetic shield which has an air gap therein to prevent the formation of a complete magnetic circuit of low reluctance, said shield being composed of a plastic matrix throughout which there is dispersed finely sub-divided magnetic material.

6. An electronic tube comprising a member having an electron-emissive coating thereon which carries no electric charge during operation of the tube, means to energize said coating to electron-emission, a cathode electrically insulated from said coating, an anode, and means to provide a magnetic field around said cathode and anode for directing the electrons emitted from said coating between said cathode and anode, said last named means comprising an inductive coil wound around said tube.

7. An electronic tube comprising an elongated trunk tube, a plurality of finger tubes secured to said trunk tube and branching away therefrom, said branching tubes having electron-emissive coatings therein which are energizable upon being raised to a mild temperature in the order of that generated by a positive column electric discharge lamp to primarily emit a copious flow of electrons, each of said branching tubes having at least one group of electrodes therein into the space between which electrons emitted by the coating are adapted to flow, and means to cause a positive column electric discharge in said trunk tube whereby to heat up said coatings for primary electron-emission.

8. An electronic tube as set forth in claim 7 wherein a portion of a branching tube extends into said trunk tube.

9. An electronic tube as set forth in claim 7

11

wherein at least one of said branching tubes is detachably secured to said trunk tube.

10. An electronic tube as set forth in claim 7 wherein at least one branching tube has a portion projecting within said trunk tube and is provided with a high heat conductivity means surrounding said portion.

11. An electronic tube as set forth in claim 7 wherein at least one of said branching tubes communicates with the interior of said trunk tube.

12. An electronic tube as set forth in claim 7 wherein at least one of said branching tubes communicates with the interior of said trunk tube and has a screening electrode disposed in the passageway connecting said trunk tube and said branching tube.

13. An electronic tube comprising an elongated trunk tube, means to cause a glow discharge in said trunk tube, and a plurality of tubes secured to said trunk tube and branching away therefrom, said branching tubes having electron-emissive coatings therein which are energized to electron-emission by the heat generated by said discharge, each of said branching tubes having at least one group of electrodes therein, at least one of the electrode groups comprising an anode and a grid telescopically around the same, the coating being disposed on the interior surface of

12

an envelope of the branching tube for said electrode group.
